UNITED STATES PATENT OFFICE.

HARRY R. BRETNAY, OF INDIANAPOLIS, INDIANA, ASSIGNOR TO JOHN WOCHER, JOHN T. DICKSON, AND JAMES S. CRUSE, ALL OF INDIANAPOLIS, INDIANA.

ALARM APPARATUS.

942,483.

Specification of Letters Patent.

Patented Dec. 7, 1909.

Application filed January 11, 1909. Serial No. 471,650.

To all whom it may concern:

Be it known that I, HARRY R. BRETNAY, a citizen of the United States, residing at Indianapolis, in the county of Marion and 5 State of Indiana, have invented certain new and useful Improvements in Alarm Apparatus, of which the following is a specification.

The object of my invention is to produce an apparatus capable of being installed in a 10 factory, or a similar place, and by means of which differentiated portions of the factory may be equipped with thermostats in a closed circuit in such manner that, if an accidental break occurs at any point in the system, a 15 notification will be delivered to headquarters indicating an accidental break, and at the local station giving an indication of the particular differentiated portion of the system wherein the break has occurred; and also of 20 such character that, upon occurrence of a fire, an easily distinguishable notification will be given to central indicating a fire as distinguished from an accidental break in the system, and an indication will be given 25 at the local station indicating the exact portion of the system wherein the fire has occurred.

The accompanying drawings illustrate my invention.

30 Figure 1 is a front elevation of the local station apparatus with the indicator face omitted; Fig. 2 a section on line 2—2 of Fig. 1; Fig. 3 a section on line 3 of Fig. 1; and Fig. 4 a diagram of the wiring for a 35 seven story and basement structure.

In the drawings, 10 indicates a suitable spring-motor of an ordinary fire alarm apparatus having a spindle 11 carrying a contact wheel 12 provided with a series of fingers 40 13 adapted to co-operate with one of a pair of contacting stationary terminals 14 and 14' in such manner as to send to a central station, such as a fire headquarters, an alarm, the possible movement of the motor being 45 sufficient to cause several successive complete rotations of the shaft 11 and then coming to a full stop when the finger 15 of the main shaft 16 comes into engagement with a fixed stop 17. The motor comprises a pallet 50 wheel 18 engaged by a pallet 19 which, in turn, carries a vibrating finger 21 adapted to be engaged by a finger 22 in such way as to prevent movement of motor. Finger 22 is carried by a bar 23 which, at its opposite 55 ends is somewhat loosely pivotally connected

to a pair of fingers 24 and 25. Finger 24 is carried by the armature 26 of an electromagnet 27 and finger 25 is similarly carried by the armature 28 of an electromagnet 29, the said armatures being normally urged 60 away from their magnets by light springs 31, so that said springs normally tend to retract finger 22 from finger 21.

Disk 12 carries a finger 41, in the path of movement of which is arranged one arm of 65 a stop lever 42 pivoted at 43 on the frame of the motor and held against movement in one direction by a pin 44. Arranged in the path of movement of the opposite end of lever 42, induced by engagement of finger 41 with 70 said lever, is a finger 45 carried by the armature 46 of an electromagnet 47.

The motor 10 comprises a driven shaft 51 (shown in dotted lines in Fig. 1) upon which is sleeved an indicator finger 52, the 75 engagement between said indicator finger and shaft 51 being sufficient to cause the indicator 52 to move with the shaft so long as movement of said indicator is unobstructed but permitting independent further movement of shaft 51 if any obstruction is brought into the path of movement of the indicator finger. The indicator finger 52 carries a metallic arm 53, which carries metallic brushes 54 and 55 which are grounded 80 on the frame of the motor and which are adapted to traverse and engage two series of terminal pins 56 and 57 arranged concentric with the axis of shaft 51. Also arranged concentric with the axis of shaft 51 85 is a series of electromagnets A, B, C, D, E, F, G, and H, corresponding in number to the subdivisions or floors A', B', C', D', E', F', G' and H' of the system to be protected. Each of the aforesaid magnets is provided 90 with an armature 58 which carries a finger 59 projectable into the path of movement of the indicator finger 52, so that, whenever anyone of the aforesaid magnets is energized, its finger 59 will be drawn down into 95 the path of movement of the indicator finger 52, so as to arrest it.

The apparatus illustrated in Fig. 1 is installed at some convenient point; the battery 61 has one of its poles connected to the 100 terminal 62 which is connected to one side of a switch 63, the other side of which is connected to terminal 64; the terminal 62 is grounded upon the main body of the structure so as to be thus connected with shaft 110

51 and brushes 54 and 55; a wire 65 leads from terminal 64 to one end of the coil of magnet 47 while the opposite end of said coil is bifurcated, one side, 66, leading to one end 5 of the coil of magnet 27, while the other side, 67, leads to one end of the coil of magnet 29; a wire 68 leads from the opposite end of the coil of magnet 27 and a wire 69 leads from the opposite end of the coil of 10 magnet 29, and these two wires 68 and 69 are carried through the territory to be protected. Each sub-division of this territory is provided with an adequate chain of thermostats 70 said thermostats being of that type where- 15 in the fusing of a fusible element will cause a break in both sides of the circuit. Wires 68 and 69 are brought together into a wire 71 at the far end of the system and returned to battery 61. The two terminals 14 and 14' 20 are connected by wires 72 and 73, respectively, with an ordinary fire alarm system connecting with fire headquarters. By this arrangement it will be noticed that the entire current of battery 61 is caused to flow 25 through the coil of magnet 47 while said current is divided between the coils of magnets 27 and 29. Under normal conditions the circuit through coils 47, 27 and 29 is closed so that finger 22 is held in the path 30 of movement of finger 21 (because armatures 26 and 28 are held down upon the magnets 27 and 29) and finger 45 is held in the path of possible movement of the long arm of lever 42. Finger 41 of disk 12 is, however, 35 initially beyond the short arm of lever 42, as clearly shown in Fig. 1.

Each of the indicator magnets A to H inclusive comprises two windings which are separate and distinct but act in the same direction on the coil. One of said windings 40 terminates in the adjacent terminal 57 while the other terminates in the adjacent terminal 56. The two windings of magnet A are connected by wires 81 and 82 respectively with 45 the wires 68 and 69 between the positive side of the battery 61 and the thermostats 70 of section A' of the system. Similarly wires 83 and 84 connect with the coils of magnet B; wires 85 and 86 connect with the coils 50 of magnet C; wires 87 and 88 connect with the coils of magnet D; wires 89 and 90 with the coils of magnet E; wires 91 and 92 with the coils of magnet F; wires 93 and 94 with the coils of magnet G, and wires 95 and 96 55 with the coils of magnet H.

In case of fire, in say section F' of the building, both sides 68 and 69 of the circuit will be broken and consequently both armatures 26 and 28 will be released so as to thus 60 release arm 21 and permit the motor to move, and the armature 46 will be released so that finger 45 will be withdrawn from the path of movement of lever 42. Thereupon shaft 11 will be rotated by the motor and projections 65 13 of disk 11 will be carried into engagement

with terminal 14 so as to intermittently withdraw it from terminal 14', thus successively breaking the fire alarm circuit 72-73 and imposing an alarm on the circuit in the usual manner. When finger 41 reaches the short 70 arm of lever 42 it will pass freely beyond said lever because of the withdrawal of finger 45 and consequently the full possible number of rotations of shaft 11 will be permitted, the motor stopping only when stop finger 15 75 comes into engagement with the stop 17.

When shaft 11 begins its rotation shaft 51 will also be rotated and the indicator finger 52 and arm 53 will rotate with it, the brushes on said arm coming first into contact with 80 and connecting terminals 56 and 57 of the coils of magnet A but, there being a break in the section F' no current can reach either coil of magnet A. The same is true of succeeding magnets and arm 52 therefore continues in its movement until brushes 54 and 55 contact with the terminals 56 and 57 of the coils of magnet F. As soon as this occurs, there being a break in the main circuit in section F', current flows from the battery 90 through wires 71 and wires 68 and 69 in parallel to wires 91 and 92 and thence through the two coils of magnet F to terminals 56 and 57 thereof; thence through brushes 54 and 55 to terminal 62, and thence to the battery, thus 95 energizing magnet F and causing the armature 58 thereof to be drawn down in the path of movement of the oncoming indicator finger 52, thus arresting the indicator finger so as to give an indication of the particular section of the building in which the fire exists. The same result may be attained by opening switch 63 but in that case there is no energization of any of magnets A to H and the indicator continues its movement until stopped 10 by pin 100. If, however, instead of a fire, there has been an accidental break in one side only of the system—say in section F'—and assuming that the break is in wire 68, the flow of current will be interrupted through 11 the coil of magnet 27 and arm 24 will thus be withdrawn so as to withdraw finger 22 from engagement with finger 21 and the motor is permitted to start, but there continues to be a flow of current through wire 69, coil of 11 magnet 29, and wire 67 through the coil of magnet 47, and consequently armature 46 is not released and finger 45 remains in its normal position so that, upon the near completion of the first rotation of shaft 11, finger 41 12 comes into engagement with the short arm of lever 42 and the long arm of said lever comes into engagement with finger 45 and is there stopped, thus arresting further rotation of shaft 11. The consequence is that 12 there has been only a single alarm imposed on the circuit 72-73 and the fire headquarters knows that, while there is trouble in the system, there is no fire.

When shaft 11 begins its rotation, shaft 51 15

will also be rotated and the indicator finger 52 and arm 53 will rotate with it, coming first into contact with, and connecting, by means of brushes 54 and 55, the terminals 56 and 57 of magnet "A" with the metal frame of the structure and thence through the terminal 62 to battery 61. There will therefore be a flow of current through one of the coils of magnet A but, because one of the 10 main lines 68 or 69 has been broken by accident, there will be no flow of current through the other coil of magnet A and the current through one coil is not sufficient to draw down the armature 58 of said magnet. Consequently, the indicator arm proceeds on its way, bringing brushes 54 and 55 successively into contact with the terminals 56 and 57 of the magnets B, C, D, E, and F. As soon as 15 brushes 54 and 55 contact with terminals 56 and 57 of magnet F there is a flow of current through both coils of magnet F, because wires 91 and 92 are connected with wires 68 and 69 between the positive side of the battery and the point of accidental break 20 in section F'. There is therefore a flow of current through both wires 91 and 92 and through both coils of magnet F, consequently causing arm 58 of magnet F to move down into position to arrest indicator 52. It will 25 be noticed that, by the expedient of the two 30 distinct windings of the indicator magnets, A to H inclusive, the connecting brushes may at all operations traverse the terminals without causing an energization of any one of the 35 magnets until that one is reached which corresponds to the point of break in either side of the system without, however, any possibility of short circuiting the two parallel 40 wires of the system.

40 1. I claim as my invention:

1. In an alarm apparatus, the combination, with means for imposing a signal upon a signal circuit, of a pair of electromagnets, means connected with both of said magnets 45 for restraining the action of the signal imposing means when both of said magnets are in the same condition but permitting movement of the signal imposing means when the two magnets are in differing condition, 50 a second restraining member for arresting the signal imposing means at an intermediate point in its possible operation, another electromagnet controlling said second restraining means, and means by which the 55 first two electromagnets may be connected each to one of the sides of a protective circuit, and the other electromagnet may be connected to both sides of the protective circuit.

60 2. In an alarm apparatus, the combination, with means for imposing a signal upon an alarm circuit, said means comprising a motor for actuating the signal imposing member, of means for normally restraining 65 said motor, a pair of electromagnets each

connected with said restraining means for withdrawal thereof upon change of condition of either electromagnet relative to the other, said electromagnets being adapted for separate connection to the two sides of a 70 protective circuit, and a second motor-restraining member arranged to engage and restrain the motor subsequent to an initial action thereof, an electromagnet controlling said second restraining member, said last 75 mentioned electromagnet being adapted for connection to both sides of the aforesaid protective circuit.

3. In an alarm apparatus, an indicator mechanism comprising an electromagnet 80 having two parallel coils each adapted to be connected to one side of a protective circuit, and each provided with an independent terminal, a brush adapted to be brought into engagement with said two terminals to bring 85 the two sides of the protective circuit together, and an indicator controlled by said electromagnet.

4. In an alarm apparatus, an indicator mechanism comprising an electromagnet 90 having two coils each adapted to be connected to one side of a protective circuit, and each provided with an independent terminal, a brush adapted to be brought into engagement with said two terminals to bring 95 the two sides of the protective circuit together, an indicator, an armature controlled by said electromagnet and adapted to be moved thereby into and out of the path of movement of the indicator to arrest said indicator, and means for driving the brush and indicator.

5. In an alarm apparatus, an indicator mechanism comprising a plurality of magnets each comprising an armature, two parallel independent coils and a pair of terminals one for an end of each coil, an indicator member comprising a terminal portion adapted to coöperate with any pair of terminals of any one of the magnets, means for 105 causing a relative movement between the terminal portion and the pairs of magnet terminals in successive coöperation, and means controlled by the magnets for arresting 110 such relative movement.

6. In an alarm apparatus, the combination, with means for imposing a signal upon a signal circuit, of a pair of electromagnets, means connected with both of said magnets for restraining the action of the signal imposing means when both of said magnets are in the same condition but permitting movement of the signal imposing means when the two magnets are in differing condition a second restraining member for arresting the 125 signal imposing means at an intermediate point in its possible operation, another electromagnet controlling said second restraining member, means by which the first two electromagnets may be connected each to one 130

of the sides of a protective circuit, and the other electromagnet may be connected to both sides of the protective circuit, an indicator driven by the signal imposing means, a brush terminal carried by said indicator, a plurality of pairs of terminals arranged to be successively traversed by said brush, a plurality of electromagnets each comprising an armature and two coils having ends connected to a pair of said last mentioned terminals, each of said armatures and the indicator member having interengaging portions whereby the indicator may be arrested in its movement by any one of the armatures.

7. In an alarm apparatus, the combination, with means for imposing a signal upon a signal circuit, of a pair of electromagnets, means connected with both of said magnets for restraining the action of the signal imposing means when both of said magnets are in the same condition but permitting movement of the signal imposing means when

the two magnets are in differing condition, means by which the said two electromagnets 25 may be connected each to one of the sides of a protective circuit, an indicator driven by the signal imposing means, a brush terminal carried by said indicator, a plurality of pairs of terminals arranged to be successively traversed by said brush, a plurality of electromagnets each comprising an armature and two coils having ends connected to a pair of said last mentioned terminals, each of said armatures and the indicator member 30 having interengaging portions whereby the indicator may be arrested in its movement by any one of the armatures.

In witness whereof, I have hereunto set my hand and seal at Indianapolis, Indiana, 40 this eighth day of January, A. D. one thousand nine hundred and nine.

HARRY R. BRETNEY. [L.S.]
